UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE FULCRUM.

Application filed September 12, 1921. Serial No. 499,935.

To all whom it may concern:

Be it known that I, WILLIAM C. HEDGCOCK, a citizen of the United States, residing at Chicago, in the county of Cook and 5 State of Illinois, have invented certain new and useful Improvements in a Reversible Fulcrum, of which the following is a specification.

This invention relates to brake beam ful- 10 crums and more particularly to fulcrums of the reversible type.

Many reversible fulcrums in use satisfactorily provide the reversible feature but permit a certain amount of lost motion in 15 the connections, which is extremely detrimental to the other important function of a brake beam fulcrum, that is, its function as a strut of the brake beam truss. Many reversible fulcrums in use also are compara- 20 tively difficult to assemble satisfactorily.

One object of my present invention is to provide a simple reversible fulcrum which is easy to assemble and which, while permitting the necessary rotative or reversing 25 movement, eliminates longitudinal lost motion from the joints which permit reversibility.

Another object is to provide a reversible fulcrum adapted to meet the various re- 30 quirements under service conditions.

These and other objects are accomplished by means of the arrangement disclosed on the accompanying sheet of drawings, in which—

35 Figure 1 is a side elevation of my improved reversible fulcrum connected to the tension and compression members which are shown in section, the fulcrum body being shown in its central position;

40 Figure 2 is a top plan view of the same arrangement, a part of the compression member being broken away to show the means for securing the fulcrum body to the compression member;

45 Figure 3 is a rear elevational view of the fulcrums with the relative position of the compression member indicated; and

50 Figure 4 is a front elevation of the fulcrum, the fulcrum being shown in one of its angular operative positions as distinguished from the central position shown in the other figures of the drawing.

The various novel features of my invention will be apparent from the following 55 description and drawings and will be par-

ticularly pointed out in the appended claims.

Referring to the figures of the drawings it will be noted that my invention is disclosed in connection with a brake beam of the truss type and including a compression member 10, a tension member 11 and a fulcrum 12 interposed therebetween. The complete connection between the tension and compression members includes the main fulcrum body 13, a thimble or pivot member 14, a clamp member 15 and a tension rod saddle member 16.

The main fulcrum body 13 has the usual brake lever receiving openings 17 and aligned pivot pin openings 18 in opposite walls of 70 the fulcrum body by means of which the lever is pivotally secured to the body. The rear end of the fulcrum body 13 is provided with a pocket 19 which receives one end of the thimble member 14, the latter being secured to the fulcrum body 13 by a rivet 20, thereby making a firm connection between the two parts in question. This thimble member 14 extends through an opening 21 in the clamp 15 and is provided with a circular head 22, the thickness of which is greater than the distance by which the intermediate portion of the bracket is offset at the point 23 with respect to the legs 24 of the clamping member by means of which 85 the latter is secured to the compression member by rivets 25. As a result thereof, this clamping arrangement eliminates any lost motion longitudinally of the fulcrum body with respect to the tension and compression 90 member, forming a rigid truss. At the same time the reversible fulcrum body 13 can be rotated or reversed by the application of sufficient force to overcome the clamping action between the head 22 of the thimble 95 member and the compression member and clamp 15.

As is known, the fulcrum body 13 when in either of its usual operative positions, is angled approximately 40° from a mid 100 position. Whatever this angle may be it is desired to limit the fulcrum against taking an increased angular position. For accomplishing this purpose the rear end of the fulcrum body is provided with a plurality of projections 26 which are adapted to engage shoulder portions 27 formed on the clamping member 15.

The front end of the fulcrum body 13 is provided with a cylindrical portion 28, the 110

end 29 of which is spherical and is received in the pocket 30 of a saddle 31 having spaced lips 32 for the reception of the tension member 11. It will be noted that the saddle member 31 is provided with an elongated opening 33 through which a portion of the spherical end 29 of the fulcrum body 13 extends so that the tension rod 11 bears directly upon the spherical end 29 of the body 13, thereby eliminating any extra joints between the tension member and the fulcrum body.

It is my intention to cover all modifications of the invention falling within the spirit and scope of the following claims.

I claim:

1. In a brake beam, the combination of a compression member, a reversible fulcrum body, a member secured to said fulcrum body, and means for clamping said member to said compression member for eliminating any lost motion between said compression member and fulcrum body longitudinally of the latter.
2. In a brake beam, the combination of a compression member, a reversible fulcrum body, a member secured thereto, and a clamp having an opening through which said member extends, said member having a head clamped intermediate said clamp and said compression member for preventing lost motion longitudinally of the fulcrum body.
3. In a brake beam, the combination of a compression member, a reversible fulcrum body, a member secured thereto, a clamp, said member having a head clamped intermediate said clamp and said compression member for preventing lost motion longitudinally of the fulcrum body, and means for limiting the movements of said reversible fulcrum body in opposite directions.
4. In a brake beam, the combination of a compression member, a reversible fulcrum body having a pocket in one end thereof, a member extending into said pocket, being secured to said fulcrum body and having a head portion, and means clamping said head portion against said compression member for eliminating lost motion between the parts longitudinally of said fulcrum body.
5. In a brake beam, the combination of a compression member, a reversible fulcrum body having a pocket in one end thereof, a member extending into said pocket, being secured to said fulcrum body and having a head portion, and means clamping said head

portion against said compression member for eliminating lost motion between the parts longitudinally of the fulcrum body, said fulcrum body and clamping means having co-operating portions for limiting reversible movements of said fulcrum body.

6. In a brake beam, the combination of a compression member, a clamping member secured thereto and having an offset portion with respect thereto, a reversible fulcrum body, and means for operatively connecting said body to said compression member, including a member having a head clamped between said compression member and clamping member, the head being greater in thickness than the offset of said clamping member whereby lost motion longitudinally of the fulcrum body is eliminated.

7. In a brake beam, the combination of a compression member, a clamping member secured thereto and having an offset portion with respect to said compression member, a reversible fulcrum body, means for operatively connecting said body to said compression member, including a member having a head clamped between said compression member and clamping member, the head being greater in thickness than the offset of said clamping member whereby lost motion longitudinally of the fulcrum body is prevented, and means for limiting the extent of reversible movement of said fulcrum body.

8. In a brake beam, the combination of tension and compression members, a reversible fulcrum body extending therebetween, a clamping connection between said fulcrum body and said compression member, and a saddle relatively rotatably mounted with respect to said fulcrum body and having an opening through which said body extends whereby said body may have direct engagement with said tension member.

9. In a brake beam, the combination of a compression member, a clamping member, and a reversible fulcrum body having an operative connection with said compression member whereby a clamping action caused by the relationship of said compression member and clamping member upon said connection prevents lost motion longitudinally of said fulcrum body.

Signed at Chicago, Illinois, this 3rd day of September, 1921.

WILLIAM C. HEDGCOCK.
